United States Patent Office

Des. 196,615
Patented Oct. 15, 1963

196,615

JAR

Arthur F. Treude, St. Louis Park, Minn., assignor to
Carlsen Engineered Products, Inc., Minneapolis, Minn.,
a corporation of Minnesota

Filed May 24, 1963, Ser. No. 75,047

Term of patent 14 years

(Cl. D58—25)

FIG. 1 is a front elevational view of a jar embodying my new design;

FIG. 2 is a side elevational view thereof;

FIG. 3 is a rear elevational view thereof; and

FIG. 4 is a top plan view thereof, the bottom being substantially plain.

I claim:

The ornamental design for a jar, as shown and described.
